DETENTION WINDOW ASSEMBLY

William D. Bayley, Springfield, Ohio

Application February 19, 1934, Serial No. 711,885

29 Claims. (Cl. 189—64)

This invention relates to window assemblies and more particularly to detention windows used in connection with penal institutions and other places where it may be desirable to prevent the egress of human bodies or foreign articles through the window.

An object of this invention is to secure strength and at the same time camouflage so as to eliminate the objectionable appearance caused by 10 closures mounted on the outside of windows having duo-functional muntin and detention bars.

Another object of the invention is to provide a plurality of sections independent of one another as far as the parallel muntin bars are concerned 15 but interlocked and camouflaged.

Another object of the invention is to provide additional detention bars across the more vulnerable area of the window and more particularly across the ventilating area which may be provided with an adjustable closure arranged to protect at least a portion thereof.

Another object of the invention is to provide 20 ventilating areas of different sizes some of which are larger than others so as to provide ventilation commensurate with the demands.

Another object of the invention is to provide a plurality of closures one for each ventilating area, at least one of said closures being hingedly attached and another pivotally attached.

Another object of the invention is to provide a ventilating area having an adjustable closure extending across the entire window and so arranged with respect to the wall that it deters tampering with the operators.

Another object of the invention is to provide a closure for a ventilating area that is of less depth than the window assembly but substantially flush with the outer surface of the window.

Another object of the invention is to provide 40 screens for the ventilating areas some of which are located on the outside and others on the inside.

Another object of the invention is to provide a screen that is snapped in position.

Another object of the invention is to provide 45 a window assembly that is cheap in construction, easily assembled, efficient in operation, and that affords adequate protection.

Another object of this invention is to provide 50 a plurality of ventilating areas having adjustable closures oppositely disposed, some of the closures being located on the inside and others on the outside.

With the above primary and other incidental 55 objects in view, as will more fully appear in the

specification, the invention consists of the features of construction, the parts and combinations thereof, and the mode of operation, or their equivalents, as hereinafter described and set forth in the claims.

In the drawings Fig. 1 discloses a front elevation of a window assembly embodying the preferred modification. Fig. 2 is an enlarged sectional view taken on the line 2—2 of Fig. 1. Figs. 3 and 4 are sectional views taken on the lines 10 3—3 and 4—4 respectively of Fig. 1. Fig. 5 is a modification disclosing a screen assembly opposite a specific type of closure. Fig. 6 discloses a view of a special nut for the screen. Fig. 7 discloses the front elevation of another modification. Fig. 8 is a sectional view taken substantially on line 8—8 of Fig. 7 but drawn to a larger scale. Figs. 9 and 10 are enlarged sectional views taken on lines 9—9 and 10—10 respectively of Fig. 7. Fig. 11 discloses another modification 15 wherein the more vulnerable area across the ventilating opening is provided with additional detention bars. Figs. 12 and 13 disclose other modifications wherein the invention has been incorporated into other than rectangular window assemblies. Fig. 14 is a sectional view taken on the line 14—14 of Fig. 13. Fig. 15 is a sectional view taken substantially on line 15—15 of Fig. 12. Fig. 16 is a sectional view taken on the line 16—16 of Fig. 13. Fig. 17 is a sectional view taken on 20 line 17—17 of Fig. 13. Fig. 18 is a sectional view taken substantially on line 18—18 of Figs. 12 and 13. Fig. 19 is a cross sectional view of the modification disclosed in Fig. 11.

When duo-functional detention bars are used 35 as disclosed in co-pending applications to Lee Bayley, Serial No. 431,117 filed February 25, 1930 now Patent No. 1,948,159 granted February 20, 1934, and Serial No. 496,709 filed November 19, 1930 now Patent No. 1,948,160 granted February 40 20, 1934, application to William Bayley Serial No. 588,155 filed January 22, 1932 now Patent No. 1,948,230 granted February 20, 1934, and applications to Zimmerman Serial No. 469,969 filed July 23, 1930 now Patent No. 1,948,152 granted February 20, 1934 and Serial No. 507,789 filed January 10, 1931, now Patent No. 1,948,153 granted February 20, 1934, all assigned to the William Bayley Company, it has been found that the closures mounted on the outside or on the inside of the 50 window present an objectionable appearance, the closures being extremely conspicuous. In the modification disclosed in this application the closures have been built into a camouflaged assembly wherein the closure although located on the 55

outside or inside as the case may be is not so conspicuous as a false frame work has been incorporated into the structure so as to make the closure appear as though it is a portion of the window proper rather than an addition thereto. In the above referred to copending applications there have been one and in some cases two closures disclosed but where two closures have been disclosed they have been shown of equal size and 10 on the same side of the window. It is very desirable in some constructions to have the closures of different sizes and one opening inwardly and the other outwardly so as to secure the proper ventilation without jeopardizing the security of 15 the window assembly.

Referring to the drawings, like reference characters have been used to indicate like parts throughout the several figures.

The reference character 20 indicates a plurality of transversely arranged muntin bars dividing the window into a plurality of spaces some of which are glazed and others at 22 and 24 unglazed forming ventilating areas. In addition to the transversely arranged muntin bars 20 a plurality of muntin bars 26 also transversely arranged form an independent section adjacent to the main section but tied thereto by a vertical U-shaped member 28 having one leg contacting the muntin bar 20 and the other the muntin bar 26. The webs of the muntin bars 20 and 26 are spanned by a projecting member 30 which leaves a void 32 forming a dead air space. Member 28, as best seen in Fig. 3, projects inwardly from the window proper and is substantially flush 35 with the inner face of the closure 34. Referring to Fig. 2 the upper cross piece 36 and the sill 38 have extensions 40 extending into the U-shaped members 28 so that the inner faces of the U-shaped members 28, members 36, 38 and 40, are substantially in one plane, thereby presenting a camouflaged appearance as though the closure is within the body of the window assembly. The sill 38 may be inserted after the window is assembled as the horizontal muntin bars passing 45 through the ventilating area are undercut at 42 which received the hooked edge or lip of the sill 38. The hooked edge of the sill 38 overlaps the inner flange of the muntin bar so as to form a suitable water shed.

50 In the modification disclosed in Fig. 2 the lower ventilating area is protected by a screen 44 carried by a frame 46 provided with grooves or notches 48 in which are seated the hooks 50 welded to the transverse muntin bars 20 and the removable hooks 52 located to engage the groove 55 on the opposite side of the frame and held in position by the screws 54 provided with a special head of which no two sides are parallel, as disclosed in Fig. 6. In this particular modification a pentagon head has been used. The screen 44 prevents or deters the cutting of these bars bounding the lower ventilating area disclosed in Fig. 1. The screen 44 hinders the inmates on the inside from removing or tampering with the putty holding in position the window panes in the glazed areas.

70 The closure 60 for the ventilating area 22 is pivoted at 62 so that the upper portion of the closure swings inwardly and the lower portion outwardly. The swinging movement of the closure 60 is limited by a suitable chain 64 and the lower portion of the closure is guided by guide member 66 carried by the muntin bars 20.

75 In order to deter the cutting of the muntin bars bounding this ventilating area which is not

screened, the muntin bars 20 are provided with reinforcing members 68 preferably of hard and tool proof material which prevents the cutting of the muntin bars 20. Likewise the upper portion of the closure 60 is provided with a reinforcing member 70 also of tool proof material to prevent the inmate from cutting the closure. 5

The lower spaces of the window in the modification disclosed in Figs. 1 and 2 have been panelled by sheet metal panels 72. If desirable these 10 could be glazed.

Referring to the modification disclosed in Fig. 5 the closure 80 is provided with a window pane 82 substantially flush, with the window panes 84 in the main portion of the window. The window 15 pane 82 is held in position by channel-shaped members 88 integral with members 90 or suitably attached thereto. Members 90 are carried by a rectangular frame 86 that is pivotally mounted upon the closure frame surrounding the vent- 20 tilating area. Removal of screws 92 permits the removal of members 88 and 90 from the frame 86. The vertical and horizontal portions of members 88 and 90 may be separated to permit the removal and replacement of the window pane 82. 25

In this modification the screen 94 is mounted upon a frame 96 one side of which is provided with studs 98 projecting into suitable apertures in the muntin bars 20 on one side of the ventilating area. The opposite side of the frame 96 30 is provided with eyes 100 receiving the screws 54 for holding the opposite edge of the screen frame in position. The screw 54 is preferably provided with a pentagonal head so as to have no two sides parallel which deters its removal. 35

Referring to the modification disclosed in Figs. 7, 8, 9 and 10 the lower closure 112 extends from wall to wall across the entire window so that the wall of the building provides an obstruction hindering the tampering with the closure operators. 40 This is especially desirable for the lower closure which is oftentimes quite accessible to the inmate. When this closure is pivoted at 114 so as to open inwardly from the top it can be readily seen that if the inmate cannot tamper with the operators 45 the closure will form an obstruction hindering the cutting of the transverse muntin bars 20. With the closure in position the inmate must assume an awkward position when cutting the muntin bars. 50

A screen 116 has been mounted outside the ventilating area. The closure 118 for the upper ventilating area when closed does not project from the outside plane of the window but is inset so as to be substantially flush with the 55 window. In this modification the screen 120 has been located on the inside of the upper ventilating area so as to prevent the inmate from cutting or reaching the transversely arranged muntin bars 122 which have been reduced in depth to 60 accommodate the closure 118. A suitable water shed 124 overhangs the upper portion of the closure to prevent rain from coming in along the upper edge of the closure. The window pane in this modification is held in place by members 88 65 similar to the disclosure in Fig. 5.

In the modification disclosed in Figs. 11 and 19 the closure 130 is pivotally mounted at 132 which pivot is located nearer the bottom of the ventilating area than the top. When the closure 70 is open as disclosed in dot-dash position the lower portion of the closure frame 134 is so located as to prevent the ready escape of the inmate through the lower half of the ventilating area. In order to prevent the escape of an inmate 75

through the upper portion of the ventilating area which may be referred to as the more vulnerable portion, detention bars 136 terminating at 138 and forming a detention grill extend across the 5 ventilating area above the pivot 132. Thus the more vulnerable portion of the ventilating area is provided with additional protection which deters the escape of inmates. This modification is very well suited for semi-detention work such as in- 10 sane asylums, hospitals, orphanages, and for that matter private homes, apartments and hotels.

In the modification disclosed in Figs. 11 and 19, the pivot of the closure is located below the center of the window. The pivot could be located above the center of the window or at the center of the window, in which event a grill like 136 could be inserted inside and below the pivot. Thus if the closure is pivoted at the center there would be one grill on the outside and one grill 20 on the inside. If the pivot is sufficiently high to prevent the escape of an inmate between the closure and the top of the window, a grill located on the inside covering the space below the pivot would be sufficient. The closure disclosed in Figs. 25 11 and 19 may be mounted in an offset frame bounding the ventilating area, similar to the frame disclosed in Fig. 8. If this is done a grill 136 may be used to protect the more vulnerable area if the muntin bars do not extend across 30 the ventilating area. If the muntin bars do extend across the ventilating area it would be necessary to cut some of the muntin bars so as to permit the lower portion of the closure to have a swinging movement into the plane of the muntin 35 bars.

Referring to Figs. 12 and 13, detention windows of other than rectangular form have been shown that are also provided with a camouflage so as to eliminate the objectionable appearance of a closure 40 mounted within the window. In these modifications the closure 150 is mounted inside of the muntin bars 20 but the remainder of the window has been provided with a false work 152 as disclosed in Fig. 14, the transverse muntin 45 bars 20 carrying members 154, shown in Fig. 16, that increases the apparent depth of the muntin bars. The inner plane of members 152 and 154 are substantially flush with the inner plane of the closure 150 and its frame 156.

50 In the modification disclosed in Fig. 14 the screen 160 is provided with a grooved frame 164 which receives the hooks 166 carried by the muntin bar bounding one side of the ventilating area. The opposite side of the frame 164 is provided with a beveled groove that receives the hook 168 beveled at 170 and carried by muntin bar 20 supported by the screws 54. The hooks 168 are of resilient material so the screen frame 164 may be snapped into position without the removal of the screws 54 but cannot very well be removed unless a special tool is provided therefor or the screws 54 removed.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to 75

be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims. 5

Having thus described my invention, I claim:

1. A detention window assembly including a 10 plurality of transversely arranged muntin bars dividing the window into a plurality of spaces some of which are glazed, leaving a plurality of spaces vacant for ventilating areas, an adjustably mounted closure for one of said areas mounted on one side of the muntin bars and an adjustable closure for another area located on the opposite side of the muntin bars whereby one closure is on the outside of the window and the other closure on the inside thereof. 20

2. A detention window including a plurality of transversely arranged muntin bars dividing the window into a plurality of spaces some of which are glazed leaving a plurality of groups of spaces vacant for the purpose of ventilation, a closure 25 for one of the ventilating areas, a frame bounding said ventilating area projecting therefrom in which the closure is adjustably mounted, a second closure for another ventilating area, said second closure being arranged to open from the 30 opposite side of the first closure and arranged so as to have the outer surface substantially flush with the outer plane of the window.

3. A detention window including a plurality of transversely arranged muntin bars dividing the 35 window into a plurality of spaces some of which are glazed leaving one group of spaces vacant as a ventilating area and a second group of spaces also vacant as a ventilating area, one of said areas having the muntin bars extending there- 40 across so as to function as detention bars, a closure located on one side of the window for closing the ventilating area having detention bars extending there-across, said closure being adjustably mounted, and a second closure for the 45 other ventilating area, said second closure being pivotally mounted intermediate the opposite sides of the ventilating area whereby the closure functions as a detention bar to prevent the easy egress or ingress of a human body through the ven- 50 tilating area.

4. A detention window including a plurality of transversely arranged muntin bars dividing the window into a plurality of spaces some of which are glazed leaving a group of spaces vacant for 55 ventilation, a second group of vacant spaces also forming a ventilating area, said second group of spaces being confined intermediate a pair of adjacent muntin bars, a screen located on one side of the first ventilating area preventing the 60 free egress of a human body therethrough, a closure for said ventilating area mounted upon the opposite side from the screen, said closure being adjustably mounted, and a second closure 65 for the second ventilating area pivotally mounted upon pivots spaced intermediate said muntin bars permitting a swinging movement of said second closure which functions as a detention bar when in open position. 70

5. A detention window assembly including a plurality of sections each section having a plurality of transversely arranged muntin bars at least one section being provided with a ventilating area across which the muntin bars extend 75

as detention bars, the muntin bars of one section being spaced away from the muntin bars of an adjacent section and a U-shaped member extending from the muntin bar of one section to the 5 muntin bar of the other section sealing the intermediate space.

6. A window assembly including a plurality of sections each of which is provided with a plurality of transversely arranged muntin bars forming spaces some of which are glazed leaving a group of spaces in at least one of the sections for ventilation across which area the muntin bars extend as detention bars, a closure frame mounted on one side of the window carrying a closure 10 extending across the ventilating area, U-shaped members spanning the spaces between adjacent sections the outer plane of the U-shaped member coinciding with the outer surface of the closure so as to present an appearance as though the closure 15 was located within the muntin bars.

7. A detention assembly including a plurality of sections having transversely arranged muntin bars dividing each section into a plurality of spaces some of which are glazed, leaving a group 20 of spaces in at least one section vacant for the purposes of ventilation, a frame adjacent the ventilating area extending outwardly from the muntin bars, a closure in said frame coincident with the ventilating area, U-shaped members inter- 25 connecting the several sections, the outer surface of the U-shaped members being substantially in the same plane as the outer surface of the closure, and means opposite the U-shaped members for closing the spaces intermediate the sections on 30 the other side of the muntin bars thereby creating a void intermediate the sections.

8. A detention window including a plurality of transversely arranged muntin bars dividing the window into a plurality of spaces some of which are glazed, leaving at least two areas vacant 40 across at least one of which the muntin bars extend as detention bars, a closure for one of the areas inset in said ventilating area so as to have its outer surface substantially flush with the outer surface of the window and a closure for the second ventilating area across which the muntin bars extend, a frame for said closure offset with respect to said muntin bars and having the closure 45 pivotally mounted therein.

9. A window assembly having a plurality of transversely arranged muntin bars dividing the window into a plurality of spaces some of which are glazed leaving at least two spaces vacant for 50 ventilating areas arranged in spaced relation from one another, and closures for said ventilating areas at least one of which is hung to open into the plane of said window and pivotally mounted medially with respect to its ventilating area, the closure cooperating with three sides of the ventilating area in making a rectangle too small for easy movement therethrough of a human body and means extending across the remaining portions of the ventilating area for preventing egress of a human body therethrough.

10. A window assembly including a plurality of transversely arranged muntin bars dividing the window into a plurality of spaces some of which are glazed leaving at least two openings in spaced relation for ventilating areas and closures for said 60 openings at least one closure hung to open into intersecting relation with the plane of the window and means for limiting the movement of said closure to prevent easy egress therethrough of a human body.

11. A detention window assembly including a 75

plurality of sections each of which includes a plurality of transversely arranged muntin bars dividing the window into a plurality of spaces at least some of which are glazed, said sections being arranged in spaced relation, and means extending from the outer muntin bar of one section to the outer muntin bar of the adjacent section for closing the space intermediate said sections. 5

12. A detention window assembly including a plurality of spaced sections each of which includes a plurality of transversely arranged muntin bars dividing the window into a plurality of spaces at least some of which are glazed and a member extending from the outer muntin bar of one section to the outer muntin bar of the adjacent section for reinforcing the window assembly.

13. In a detention window assembly including a plurality of transversely arranged muntin bars dividing the window into a plurality of spaces some of which are glazed leaving a group of spaces vacant for ventilating area across which the muntin bars extend as detention bars, the muntin bars bounding the ventilating area having integral projecting flanges forming a frame and an adjustably mounted closure cooperating with said projecting flanges to close the ventilating area.

14. In a detention window assembly including a plurality of transversely arranged muntin bars dividing the window into a plurality of spaces some of which are glazed leaving a group of spaces vacant for ventilating area across which the muntin bars extend as detention bars, the muntin bar extending across the bottom of the 35 ventilating area being provided with an integral projecting flange and an adjustably mounted closure mounted upon said flange for closing the ventilating area.

15. A window assembly including a plurality of spaced sections each of which includes a plurality of transversely arranged muntin bars dividing the window into a plurality of spaces some of which are glazed leaving a group of spaces in at least one of said sections for a ventilating area, 40 projecting members spanning the spaces intermediate adjacent sections, and a camouflage frame extending from at least one of said members into overlapping relation with respect to the ventilating area and a closure adjustably mounted in said frame for closing said ventilating area said frame and said members cooperating to disguise the window assembly.

16. A detention window assembly including a plurality of transversely arranged muntin bars dividing the window into a plurality of spaces some of which are glazed, leaving at least a group of spaces vacant for ventilating area across which the muntin bars extend as detention bars, a camouflage frame carried by the window assembly including members extending parallel to the muntin bars bounding the ventilating area some of said members extending beyond the ventilating area and a closure mounted in said camouflage frame 60 for closing the ventilating area.

17. In a detention window assembly including a plurality of transversely arranged muntin bars dividing the window into a plurality of spaces some of which are glazed leaving a group of spaces 70 vacant for ventilating area across which the muntin bars extend as detention bars, a camouflage frame extending across the window in proximity to the ventilating area said camouflage frame extending in overlapping relation with 75

- glazed portions of the muntin bars so as to disguise the ventilating area.
18. In a detention window assembly including a plurality of transversely arranged muntin bars dividing the window into a plurality of spaces some of which are glazed leaving a group of spaces vacant for ventilating area across which the muntin bars extend as detention bars, a camouflage frame carried by the muntin bars bounding the ventilating area, said camouflage frame extending beyond the ventilating area so as to disguise the same and a movably mounted closure mounted in said camouflage frame for closing the ventilating area.
19. In a detention window assembly including a plurality of transversely arranged muntin bars dividing the window into a plurality of spaces some of which are glazed leaving a group of spaces vacant for ventilating area across which the muntin bars extend as detention bars, a camouflage frame mounted adjacent the ventilating area but extending theret beyond and a movably mounted closure carried in said frame for closing the ventilating area.
20. A detention window assembly including a plurality of transversely arranged muntin bars disposed in sections to divide each section into a plurality of spaces, at least some of which are glazed, leaving an unglazed space intermediate adjacent sections, and means for closing the space intermediate adjacent sections.
21. A detention window assembly including a plurality of transversely arranged muntin bars arranged in sections, said muntin bars dividing each section into a plurality of spaces, at least some of which are glazed, the sections being arranged in spaced relation so as to leave an unglazed space therebetween, and a plurality of members for closing the spaces intermediate adjacent sections.
22. A detention window assembly including a plurality of transversely arranged muntin bars sectionally arranged dividing the window into a plurality of spaces, at least some of which are glazed, the sections being arranged in spaced relation from one another, and a U-shaped member joining adjacent sections.
23. A detention window assembly including a plurality of sections, each of which has a plurality of transversely arranged muntin bars dividing the sections into a plurality of spaces, at least some of which are glazed, and means for interlinking adjacent sections, said means including a U-shaped member and a second member cooperating with said U-shaped member to form a dead air space between sections.
24. A window assembly including a plurality of sections arranged in spaced relation, each of said sections including a plurality of transversely arranged muntin bars, the outer muntin bar of at least one of said sections being T-shaped, and means cooperating with said T-shaped muntin bar for uniting said section to the adjacent section.
25. A window assembly including a plurality

of sections arranged in spaced relation, each of said sections including a plurality of transversely arranged muntin bars, the outer muntin bar of at least one of said sections being T-shaped, and means interconnecting the stem and the flange of said T-shaped muntin bar to the adjacent section. 5

26. A window assembly including a plurality of transversely arranged muntin bars dividing the window into a plurality of spaces some of which are glazed leaving a group of spaces vacant for ventilating area, a frame for said window assembly in which the muntin bars are mounted, at least a portion of said frame being arcuate and a closure assembly for the ventilating area, the 10 muntin bar extending across one side of the ventilating area supporting a projecting flange extending intermediate at least two glazed spaces and an extension carried by the muntin bar on the opposite side of the ventilating area, said extension being limited to the ventilating area. 15

27. A window assembly including a plurality of transversely arranged muntin bars dividing the window into a plurality of spaces some of which are glazed leaving at least two groups of 25 spaces vacant for ventilating areas, a frame for said window assembly in which the muntin bars are mounted, at least a portion of said frame being arcuate and closure assemblies for the ventilating areas, the muntin bar extending 30 across one side of the ventilating areas, supporting a projecting flange extending intermediate at least two glazed spaces and an extension carried by the muntin bar on the opposite side of the ventilating area, said extension being limited to 35 the ventilating area.

28. A window assembly including a plurality of transversely arranged muntin bars dividing the window into a plurality of spaces some of which are glazed leaving a group of spaces vacant 40 for ventilating area, a frame for said window assembly in which the muntin bars are mounted, at least a portion of said frame being arcuate and a closure assembly for the ventilating area, the muntin bar extending across one side of the 45 ventilating area supporting a projecting flange extending across at least two glazed spaces and a muntin bar on the opposite side of the ventilating area being differently shaped in different portions of its length. 50

29. A detention window assembly including a plurality of transversely arranged muntin bars dividing the window into a plurality of spaces, some of which are glazed, leaving a group of spaces vacant for ventilating area, and a closure 55 for said ventilating area hung to open into the plane of said window and pivotally mounted medially with respect to its ventilating area, the closure cooperating with the three sides of the ventilating area in making an opening too small 60 for easy movement therethrough of a human body and means extending across the remaining portion of the ventilating area for preventing egress or ingress of a human body therethrough. 65

WILLIAM D. BAYLEY. 65
